FIBER CONTAINER WITH SIDE SEAM OPENING AND RECLOSED FEATURE

Malcolm C. Allen, Westport, Conn., and Donald G. Magill, Great Neck, N. Y., assignors to American Can Company, New York, N. Y., a corporation of New Jersey

Application August 1, 1949, Serial No. 107,864

3 Claims. (Cl. 229—51)

1

The present invention relates to fibre containers of the variety used for frozen food products, cottage cheese, and many other commodities, and has particular reference to such a container that may be opened and reclosed at the side seam of the container body.

An object of the invention is the provision of a fibre container having a side seam and side wall construction whereby the container may be readily opened by a mere prying apart of the laps of the side seam and reclosed by a repositioning of the side seam portions or laps of the container.

Another object is the provision of such a container wherein the repositioned side seam portions of the container may be locked together in such a manner as to retain them in their repositioned relation and thus provide a complete reclosure for the container.

Another object is the provision of such a container wherein locking ledges are set off by score lines disposed transversely of the seam so that upon separation of the side seam portions of the container body the score lines are ruptured and the ledges are fully exposed for interlocking the seam portions when they are repositioned for reclosing the container.

Another object is the provision of such a container wherein clearance notches are provided at the terminal ends of the score lines to facilitate separation of the seam laps without damaging portions of the seam beyond those laps and which portions serve as locking ledges.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a sealed container embodying the instant invention in the side wall which contains the lap seam.

Fig. 2 is a fragmentary view similar to Fig. 1 showing the container in an opened condition;

Fig. 3 is a view similar to Fig. 2 showing the container in a reclosed condition;

Fig. 4 is an enlarged sectional detail taken substantially along a plane indicated by the lines 4—4 in Fig. 1;

Figs. 5, 6 and 7 are perspective views similar to Figs. 1, 2 and 3 and disclose a modified form of the invention; and

Fig. 8 is an enlarged sectional detail taken substantially along a plane indicated by the lines 8—8 in Fig. 5.

2

As a preferred or exemplary embodiment of the invention Figs. 1, 2, 3 and 4 of the drawings illustrate a container comprising a fibre tubular body 11 of rectangular shape, having metallic end members 12 secured thereto in suitable end seams 13. The body preferably is formed from a single blank of sheet material having side seam marginal edge portions 14, 15 overlapped and adhesively secured together by a band of adhesive 16 to provide a lapped side seam 17. The ends of the seam preferably are incorporated in the end seams 13.

The band of adhesive 16 preferably is set back a short distance from the outer edge of the upper or outer flap or seam portion 14 so as to leave a narrow section 18 (Fig. 2) unsecured to the lower or inner flap or seam portion 15. Adjacent the end members 12, the body 11 is provided with score lines 21, 22 which are disposed at an angle to and extend toward and across the side seam 17. These score lines preferably are parallel to and spaced from each other.

There are two score lines 21, disposed one adjacent each end member 12 preferably at right angles to the side seam 17 and they extend from one corner of the body into and through the upper or outer seam or lap portion 14 (Figs. 1 and 4) to define the lateral edges of an upper or outer opening flap in the body. The terminal ends of these score lines extend into clearance notches 23 formed in the terminal edge of the seam or lap portion 14.

There are also two score lines 22, disposed one adjacent each of the score lines 21 preferably at right angles to the side seam 17 and they extend from the opposite corner of the body into and through the lower or inner seam portion or lap 15 (Figs. 1 and 4) to define the lateral edges of a lower or inner opening flap. Each of these score lines 22 are spaced inwardly of its corresponding score line 21 in an offset relation to provide a projection or ledge 25 at each end (Fig. 2) as will be hereinafter explained.

When it is desired to open the container it is merely necessary to insert a flat tool such as a knife, letter opener, etc. under the unsecured section 18 of the side seam 17 and run it along the seam from one notch 23 to the other. In this manner the outer seam portion or lap 14 may be pried loose and separated from the inner seam portion or lap 15, thus rupturing or opening the seam. The notches 23 serve as clearance or outlet spaces for the knife and thus prevent separation of the seam beyond the portion

to be opened, leaving the seam terminals adjacent the end members 12 intact. With the side seam between the notches 23 ruptured, the loose seam portions 14, 15 may be readily lifted upwardly as shown in Fig. 2 to open the entire side of the container to gain access to its contents. This lifting of the seam portions 14, 15 ruptures the score lines 21, 22 and exposes the offset ledge or projection 25 (Fig. 2) adjacent each end of the container. These ledges 25 are in fact undisturbed projections or remnants of the inner seam portion 15 and are utilized in reclosing the container.

To reclose the container it is merely necessary to reposition the loose side seam portions 14, 15 in their original overlapped position and press or push them down into the container a short distance just below the ledges 25 as best shown in Fig. 3. In this manner the outer seam portion 14 is engaged under the ledges 25 and is locked in position thereby. The outer seam portion thus holds the inner seam portion in position and the container is thereby effectively closed, the ledges 25 serving as locking ledges for holding both seam portions 14, 15 in closed position.

As a modified form of the invention Figs. 5, 6, 7 and 8 of the drawings disclose a container similar to that shown in Figs. 1, 2, 3 and 4. In this modified form of the invention the side seam 17 is traversed by score lines the major portions of which coincide or are in alignment with each other. For this purpose the container body 11 is formed with a pair of straight score lines 27 (Figs. 5 and 8) disposed one adjacent each end member 12 preferably at right angles to the side seam 17 and extending from one corner of the body into and through the lower or inner seam portion or lap 15.

The body 11 is also formed with a pair of score lines 28 which are coincident with or in alignment with the score lines 27 for a major portion of their length and extending from an opposite corner of the body into and through the upper or outer seam portion or lap 14. If desired these score lines may terminate in clearance notches formed in the terminal edge of the outer seam portion 14 as shown in the preferred form of the invention. In the outer seam portion 14 the score lines 28 preferably curve outwardly along a curved line 29 which sets off in the seam portion 14 a tab or lug 31 which extends beyond the score line 27 in the inner seam portion 15.

Hence when the container is opened by rupturing the side seam 17 with a flat tool and the separated seam parts lifted as disclosed in the preferred form of the invention, the tabs 31 in the outer seam portion 14 are broken loose from the inner seam portion 15 and thereby expose a projecting ledge 32 (Fig. 6) adjacent each end of the container for use in reclosing the container.

Thus when the container is reclosed by a repositioning of the loose side seam portions 14, 15 in their original overlapped position and a pressing or pushing of these overlapped portions down into the container, the tabs 31 snap past the ledges 32 and engage under the ledges as best shown in Fig. 7. In this manner the tabs 31 and ledges 32 lock the outer seam portion 14 in place and the outer seam portion holds the inner seam portion 15 in place, thus effectively reclosing the container.

If desired the tabs 31 may be formed in the

5
10
15

inner seam portion 15 instead of the outer seam portion 14 and in both cases the tabs could extend inwardly instead of outwardly with equal results.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. A readily opened and reclosable container of rigid fibre and sheet metal construction per se, comprising in combination a tubular fibre body of rigid fibre having a side seam formed from overlapping marginal portions of the body which are adhesively secured over at least a portion of the overlapping area and also constitute in part inner and outer opening flaps, separate sheet metal and members secured to the opposed end edges of said rigid fibre body in end seams, a pair of axially spaced score lines extending through said outer flap and beyond said overlapped area into the body material and also spaced inwardly from said end seams, a second pair of axially spaced score lines extending through said inner flap and beyond said overlapped area into the body material and at least portions of said second pair of score lines in said overlapped area being spaced inwardly from corresponding portions of said first pair of score lines, the differential spacing of said pairs of score lines from said end seams providing a rigid locking ledge in the body material of the undisturbed remainder of the inner lap of said overlapping marginal portions thereby permitting the outer flap to be locked under said ledge as a reclosure after the flaps have been separated from their adhesive connection and severed along said pairs of score lines.

2. A readily opened and reclosable container of rigid fibre and sheet metal construction per se, comprising in combination a tubular fibre body of rigid fibre having a side seam formed from overlapping marginal portions of the body which are adhesively secured over at least a portion of the overlapping area and also constitute in part inner and outer opening flaps, separate sheet metal end members secured to the opposed end edges of said rigid fibre body in end seams, a pair of axially spaced score lines extending through said outer flap and beyond said overlapped area into the body material and also spaced inwardly from said end seams, a second pair of axially spaced score lines extending through said inner flap and beyond said overlapped area into the body material each score line of said second pair being spaced inwardly from its adjacent end seam a greater distance

55
60
65
70
75

than its corresponding score line of said first pair of score lines, the differential spacing of said pairs of score lines from said end seams providing narrow locking ledges in the body material of the undisturbed remainder of the inner lap of said overlapping marginal portions thereby permitting the outer flap to be locked under said ledges as a reclosure after the flaps have been separated from their adhesive connection and severed along said pairs of score lines.

3. A readily opened and reclosable container

of rigid fibre and sheet metal construction per se, comprising in combination a tubular fibre body of rigid fibre having a side seam formed from overlapping marginal portions of the body which are adhesively secured over at least a portion of the overlapping area and also constitute in part inner and outer opening flaps, separate sheet metal end members secured to the opposed end edges of said rigid fibre body in end seams, a pair of axially spaced score lines extending through said outer flap and beyond said overlapped area into the body material and also spaced inwardly from said end seams, a second pair of axially spaced score lines extending through said inner flap and beyond said overlapped area into the body material and spaced inwardly from said end seams a distance substantially equal to that at which said first score lines are spaced from said end seams, portions of only said first score lines in the overlapping area of the outer flap being offset toward their adjacent end seams and thus spaced from corresponding portions of said second score lines said offset portions of the first score lines; outlining locking lugs on said outer flap, the differential spacing of said corresponding portions of the pairs of score lines

from said end seams providing locking ledges in the body material of the undisturbed remainder of the inner lap of said overlapping marginal portions thereby permitting said lugs on the outer flap to be locked under said ledges so that said outer flap serves as a reclosure after the flaps have been separated from their adhesive connection and severed along said pairs of score lines.
